UNITED STATES PATENT OFFICE.

CARL EPPS, OF ATHENS, GEORGIA, ASSIGNOR TO CLIMAX HOSIERY MILLS, OF ATHENS, GEORGIA, A CORPORATION OF GEORGIA.

REVERSE-PLAITING KNITTING MACHINE.

Application filed June 3, 1924. Serial No. 717,466.

This invention relates to knitting, and, more concisely stated, is concerned with the production of pattern effects by the plaiting method involving simultaneous feeding 5 of two or more yarns of different kinds distinguishable in the knitted fabric by contrast of quality, finish, or color. To obtain pattern effects by the plaiting method heretofore, it has been generally customary to 10 employ a body yarn to provide the base of the fabric, and to plait upon such base with the contrasting yarns. Such procedure, as is well understood by skilled knitters, requires cutting with each interchange of the 15 yarns employed in plaiting thereby leaving objectionable loose ends at the regions where substitutions take place. The main object of my invention is to enable production of pattern effects by plaiting without necessitating 20 any change or cutting of yarns whatever; and this desideratum is attained by simultaneously and continuously feeding several 25 yarns with incidental manipulation between them, whereby the feeding relation is varied to determine appearance of one or another upon the face of the fabric in accordance with the pattern desired.

The invention is also concerned with means whereby plaiting, modified in accordance 30 with the above considerations, may be conveniently carried out.

Other objects together with attendant advantages accruing to my invention will be manifested in the detail description which 35 follows of a typical embodiment thereof, the appended claims serving to define those features which I believe to be novel and therefore patentable.

In the drawings Fig. I is a side elevation 40 of a standard type of circular stocking knitting machine with the present invention applied thereto.

Figure II is a front elevation of the machine, certain portions being broken away 45 and illustrated in section so as to avoid concealment of important details.

Fig. III is a plan view of the tension device forming a part of the means whereby the yarns are manipulated in the course of 50 being simultaneously and continuously fed to the needles of the machine.

Fig. IV is a front elevation of said tension device.

Fig. V is a side elevation of the same as 55 viewed from the left of Fig. III.

Fig. VI is a cross sectional view taken as indicated by the arrows VI—VI in Fig. III.

Fig. VII shows a stocking knit in accordance with my invention; and,

Fig. VIII is a diagrammatic illustration 60 of the fragment of the fabric bounded by the dotted rectangle VIII in Fig. VII.

The machine herein shown is equipped with a cylinder 1 for guidance of needles 2, said cylinder being adapted to be driven in 65 the usual way by belt power applicable to pulleys 3 mounted on the main drive shaft 4, that is appropriately journaled in the machine frame, comprehensively designated by the numeral 5. The machine may also 70 comprise a series of yarn feeds, one such being shown—at 6 in Fig. II—as pivoted upon a fulcrum axis 7, carried by the retractable latch guard ring 8 that normally overhangs the needle cylinder 1. The yarn feed 6 is, 75 after common practice, operable from beneath by a lever 9 fulcrumed at 10 to a fixed standard 11 whereto the latch guard 8 is pivoted, said standard rising vertically from the bed plate 12 which supports the needle 80 cylinder 1. Motion is imparted to the lever 9 through an interposed downwardly extending rod 13 connected to a finger 14 that is fulcrumed on a fixed stud 15 and lies in the path of a cam projection 16 on a rotatable drum 17. This drum 17 is fixed to the counter-shaft 18 that carries the sprocket wheel 19 for the pattern chain 20 whereby the various sub-mechanisms of a knitting machine of this character are controlled in 85 the usual manner. The yarn feed 6, herein shown, is doubly pierced as at 21, 22 so as to be capable of simultaneously directing two yarns Y, Y' of different kinds (in this instance of contrasting colors), to the needles 90 2 of the machine, guidance en route to the feed 6 being assisted by an apertured plate 23 sustained at a suitable elevation by the latch guard 8.

The yarns Y, Y' are supplied from bobbins B, B' supported upon an extension bracket 24 of the machine frame 5, and previous to being fed to the needles 2, are subjected to the action of a reversible tension device generally indicated by the numeral 25. 100 This device 25 is arranged for attachment to the branched top member 26 of the yarn guide tree which may be of conventional construction and mounted to the upper end of a fixed stem or post 27. The tension de- 105

110

vice 25 comprises an angular bracket 28 whose vertical leg is formed with a laterally projecting lug 29 whereby it may be conveniently secured to the tree member 26 with the aid of one or more screws 30. As shown in Figs. III to V, from each side of the horizontal portion of the bracket 28 depend a series of spaced integral ears 31 to each of which is fastened a spool-shaped friction member 32 preferably of porcelain or other similar smooth hard-surfaced material, the axial screws 33 employed in securing said friction members serving to hold them fixed against rotation. Pivoted 10 mounted in opposed relation between common bearing lugs 34, 35, respectively at opposite ends of the horizontal portion of the bracket 28, are two independently-swingable multi-armed yarn guide members 36, 37 each 20 comprising a longitudinal bar 38 from which the extremities 39 project. At the end of each of the extremities 39 is secured a guide eye 40, and it is to be observed that in each instance the extremities 39 are alternately 25 disposed with regard to the respective groups of the friction members 32 with which they are designed to cooperate. The pivoted guide members 36, 37 are subject to springs 41, 42 extending from collars adjustable on vertical posts 43, said posts being appropriately anchored in the bracket 28. The springs 41, 42 tend to draw upon the guide members 36, 37 so that the latter carry the yarns Y, Y' into contact respectively 35 with the corresponding series of friction members 32, screws 44 adjustable in the bracket 28 functioning to limit the free upward movement of said yarn guide members. To the front of the bracket 28 is pivoted a 40 double-armed rock lever 45 having its ends turned laterally as at 46, 47 so as to overlie the contiguous extremities 39 of the yarn guide members 36, 37 as shown in Figs. III and IV. Thus as the rock lever 45 is swung 45 clock-wise about its pivot in accordance with Fig. IV against the pull of a contractile spring 48, its end 47 depresses the yarn guide 37 to carry the yarn Y' below the province of the corresponding group of friction members 32; while at the same time, the end 46 of said lever is elevated to an extent sufficient to release the yarn guide member 36 to its spring 41 so that the yarn Y is carried upwardly into engagement with the 50 group of friction members 32 at that side of the device 25. With the various parts positioned as just described, it will be seen that the yarn Y' is permitted to run slack, while the yarn Y is tensioned to the extent of the 55 friction imposed thereupon by virtue of the devious or undulatory course which it is obliged to follow in passing about the group of friction members 32 with which the yarn guide member 36 is associated. As a result 60 of this difference in relative tensions, the 65

yarn Y is plaited upon the yarn Y' and therefore appears on the face of the fabric. When the lever 45 is swung in the opposite direction to depress the guide 36 and concurrently release the guide 37 the tensional or feeding relation of the yarns Y, Y' will be directly reversed, i. e., tension being then on the yarn Y' while the yarn Y is permitted to run slack with corresponding positional change of the yarns in the fabric. 75 Referring again to Figs. I and II it will be noted that the yarns Y, Y' in being drawn from the bobbins B, B' are passed for directional guidance through depending guides 49 of the tree member 26 so as to enter the eyes 40 of the swingable yarn guides 36, 37 of the device 25 substantially in a direct line without imposing any drag thereon. 80

As a convenient means for controlling the rock lever 45 of the tension device 25 to selectively actuate the yarn guides 36, 37, I may employ special links 50 on the pattern chain 20, said special links 50 having cam rises 51 adapted to successively swing a finger 52 about a fulcrum stud 53 on the machine frame 5. A leaf spring 54 secured to the inner side of the machine frame 5 and bearing against a projection 55 of the finger 52, acts to maintain the latter at all times in operative engagement with the pattern chain 20. The movements of the finger 52 are transmitted through a connecting rod 56 to the rock lever 45 of the tension device 25, said rod being composed of two parts relatively adjustable through interpolation of a double-apertured slide collar 57 provided with set screws 58. 90

In operation, as the pattern chain 20 is intermittently progressed by the usual mechanism (not shown) provided for this purpose, the high links 50 are successively brought beneath the finger 52 with the result that the latter is swung to draw the rod 56 downwardly and thereby position the rock lever 45 of the tension device 25, as shown in full lines in the several illustrations. When the finger 52 drops off a special link 50 on to a succeeding plain link of the chain 20, the rock lever 45 is swung counter-clock-wise to reverse the tensional feeding relation of the yarns Y, Y' as already explained. As a result of such periodic operation, the stocking produced by the machine will be characterized by contrasting horizontal stripes as shown at S, S' in Fig. VII, 105 the exact relation of the yarns Y, Y' in the fabric being diagrammatically illustrated in Fig. VIII. A pattern chain 20 with alternating high and plain links, such as herein shown, obviously determines stripes of uniform width, since the tensional reversal of the yarns is obliged to take place periodically at regularly recurring intervals. Variation may, however, be had by lengthening the intervals between the special links 50, for 110 115 120 125

example, by inserting more than single intervening plain links in the pattern chain 20 to determine stripes of different widths. Still further variations are possible by use of 5 special links arranged, as herein illustrated but with shorter rises; or again by combining the several arrangements suggested. Moreover, if desired, plaiting may be practised in accordance with my invention in 10 alternation with other forms of knitting by employment of additional interchangeable feeds such as ordinarily associated with a double feed of the type illustrated in standard knitting machines, thereby permitting 15 occasion substitution of other yarns in place of the simultaneously fed yarns Y, Y' under governance of the feed control drum 17.

From the foregoing it will be appreciated 20 that my invention is readily applicable to all modern types of knitting machines without requiring any changes or alterations in them other than possible of easy accomplishment by any mechanic schooled in the knitting arts.

25 Having thus described my invention, I claim:

1. The combination in a knitting machine equipped with needles and actuating mechanism therefor, of automatically operative means effective to alternately tension and slack feeding yarns of different kinds to determine alternate appearance of one or another of said yarns on the face of the fabric; said means comprising a bearing 30 bracket with spool-like friction members, individual guides independently swingable to vertically elevate the yarns respectively into and out of engagement with the friction members, and pattern means controlling 35 movement of said guides to vary the tension and slack feeding relation as between the 40 yarns.

2. The combination in a knitting machine equipped with needles and actuating mechanism therefor, of automatically operative means effective to alternately tension and slack feeding yarns of different kinds to determine alternate appearance of one or another of said yarns on the face of the fabric; said means including a bracket supporting spool-like friction members, opposed independently swingable multi-armed guides pivoted in the bracket with the arms alternating between the friction members and 50 having terminal eyes adapted to carry the yarns respectively into and out of engagement with the friction members, and pattern means controlling swinging of the guides to vary the tension and slack feeding relation 55 as between the yarns.

60 3. The combination in a knitting machine equipped with needles and actuating mechanism therefor, of automatically operative means effective to alternately tension and

slack feeding yarns of different kinds to determine alternate appearance of one or another of said yarns on the face of the fabric; said means comprising an angle bracket supporting stationary friction members, a multi-armed guide for each yarn pivoted in the 65 bracket with the arms thereof alternating between the friction members, individual springs influencing the guides to normally carry the yarns into engagement with the friction members, and pattern means for 70 controlling selective actuation of the guides to withdraw corresponding yarns from said friction members.

4. The combination in a knitting machine equipped with needles and actuating mechanism therefor, of automatically operative means effective to alternately tension and slack feeding yarns of different kinds to determine alternate appearance of one or another of said yarns on the face of the fabric; said means comprising a bracket with ears stationarily supporting spool-like friction members, an independently pivoted guide for each yarn with arms alternately disposed with respect to the friction members, individually associated springs influencing the guides to normally carry their yarns into engagement with the friction members, a rockable double-armed lever with its terminal ends overlying and adapted to swing the guides alternatively to withdraw their respective yarns from the friction members, and pattern means controlling actuation of said lever.

5. The combination in a knitting machine equipped with needles and actuating mechanism therefor, of automatically operative means effective to alternately tension and slack feeding yarns of different kinds to determine alternate appearance of one or another of said yarns on the face of the fabric; said means comprising an angular bracket with depending ears sustaining spool-like friction members, a multi-armed, independently swingable guide for each yarn pivoted between common bearing lugs on the aforesaid bracket, individual springs influencing the guides to normally carry their yarns into engagement with the friction members, a double-armed rockable lever having its terminals laterally turned to overlie the contiguous ends of and swing the guides alternatively to withdraw their respective yarns from the friction members, a pattern control chain with special high links, a spring influenced finger subject to said links, and a connecting rod whereby movement of the finger is transmitted to the rockable lever aforesaid.

In testimony whereof, I have hereunto signed my name at Athens, Georgia, this 27th day of May, 1924.

CARL EPPS.
